UNITED STATES PATENT OFFICE.

BENJAMIN F. VANDERSLICE, OF DARBY, PENNSYLVANIA.

TRESTLE FOR TABLES, SCAFFOLDING, &c.

1,113,264.

Specification of Letters Patent.

Patented Oct. 13, 1914.

Application filed April 1, 1913. Serial No. 758,133.

To all whom it may concern:

Be it known that I, BENJAMIN F. VANDERSLICE, a citizen of the United States, residing at Darby, in the county of Delaware, State of Pennsylvania, have invented a new and useful Trestle for Tables, Scaffolding, &c., of which the following is a specification.

My invention consists of a trestle which is formed of a central column, horizontally extending arms radiating therefrom, and legs adapted to extend perpendicular to said arms and hinged thereto, thus forming a strong structure for supporting a table, board, etc., with spread apart members which will prevent the trestle from over-turning or shifting and presenting a flush top of said column and the upper arm-members, and providing a flat surface for the support of said table, board, etc., while the upper thrust of each leg is resisted by the entire abutting end faces of the arms both against the column and legs, the leg and arm-members being adapted to be folded on the central column forming a bundle that is compact and of vastly reduced diameter.

The invention is satisfactorily illustrated in the accompanying drawing, but the important instrumentalities thereof may be varied, and so it is to be understood that the invention is not limited to the specific arrangement and organization shown and described.

Figure 1 represents a perspective view of a trestle in operative condition embodying my invention. Fig. 2 represents a side elevation of the same in folded condition. Fig. 3 represents a side elevation of the upper portion of the trestle in operative condition.

Similar numerals of reference indicate corresponding parts in the figures.

Referring to the drawings, 1 designates a column occupying the center of the trestle, the same being of angular form in cross section, producing numerous sides 2 in the present case, four in number.

3 designates arms which are connected with the upper portion of the column 1 by the hinges 4, and 5 designates arms which are connected with the lower portion of said column by the hinges 6, said arms being adapted to radiate from said column.

7 designates legs which are connected with the arms 3 by the hinges 8, said legs being furthermore connected with the arms 5 by the hinges 9, it being noticed that the butts

of the hinges 4 are connected respectively with the column 1, and the undersides of the arms 3, that the upper butts of the hinges 5 are connected respectively with the column 1 and with the undersides of the arms 5, that the butts of the hinges 8 are connected respectively with the outer sides of the legs 7 and the undersides of the arms 3, and that the butts of the hinges 9 are connected respectively with the upper sides of the arms 5, and the inner sides of the legs 7 consequently the trestle may be folded, as shown in Fig. 2. When the column is raised, the arms 3, the legs 7, and arm 5 assume downward positions, as shown in Fig. 2, placing the trestle in narrow form convenient for storage, transportation, etc.

When the trestle is required for service, the arms are drawn out to horizontal positions and the legs to vertical positions. The column 1 lowers and sets flat on a floor or ground, as do also the legs 7, the trestle producing a wide or broad structure which is not liable to overturn or fold, the weight of the arm and leg members causing a downward thrust of the same flat on the floor or ground while the arms 5 abut laterally against the column and legs and the arms 3 abut laterally against the column and upon the tops of the legs, the arms having their thrust bearing against the column, the entire depth of the end faces of said arms thus bracing said legs and arms and stiffening the construction of the trestle. As the upper arms 3 are imposed upon the tops of the legs 7, as has been stated, they load said legs from above and so forcibly press the same upon the floor or ground, so as to cause the trestle to set firmly in position, and prevent it from shifting, these desirable conditions being increased when a table, board, etc., is placed on the trestle. Furthermore, as the arms 3 are above the top of the legs 7, their upper sides are flush with the top of the column 1 and so the top of the trestle presents a flat support for the table, board, etc., imposed thereon.

The hinges 4 have their upper butts secured to the under sides of the upper arms 3, and their lower butts secured to the sides of the column. Said arms turn down and up on the pintles of the hinges and so are not pierced or bored through and thereby weakened by pivot pins passed through the same, they being sustained on said pintles and so firmly supported without liability of said

2
pivot pins grinding out the wood of the arms 3 about said pivot pins as such pivot pins in the wood are dispensed with and so the arms are left intact. Then, the lower butts of the 5 said hinges are secured to the column below the top thereof, so that the inner ends of the arms 3 when in horizontal position abut solidly against the sides of said column and their upper sides are flush with the top of 10 the column, as shown in Fig. 1, as has been stated. Again, in order to increase the surfaces of the upper arms 3 for the support of a table, board, etc., thereon, the outer end portions 10 of said arms 3 are extended be- 15 yond the outer sides of the legs 7, so as to overhang the same, see Fig. 1, while also providing increased room for the connection of the butts of the hinges 8 therewith, see Fig. 2, and removing said butts from being 20 seated on the tops of said legs.

Attention is directed particularly to the fact that in the folded condition of the trestle the upper arms 3 are hinged to the central column below the top thereof, so that 25 in the operative condition thereof, the inner ends of said arms, in their horizontal positions, abut solidly against said column, and the top of the latter is exposed or uncovered leaving said top and the upper sides of said 30 arms 3 flush, whereby the weight imposed on the trestle is received solidly on the central column as well as on the top arms, said column being immovable, and said upper arms being prevented from sagging on their inner

ends thereby relieving said arms and the 35 hinges connected therewith of downward strain and providing the trestle with an unbroken top surface, which will prevent wobbling or tilting of the table, board, etc., on said surface.

Having thus described my invention what 40 I claim as new and desire to secure by Letters Patent, is:

A trestle composed of a central vertical column, upper and lower outwardly extending arms and vertical legs, similar butt hinges throughout, connecting said arms with said legs and column respectively, the inner 45 hinges of said arms having their butts secured respectively to the under sides of said 50 arms and the sides of said column below the arms causing said arms, when in operative position, to have thrust bearing against the column throughout the entire depth of the arms; the hinges of the lower arms connect- 55 ing the latter with said legs and column being staggered on said lower arms, both upper and lower arms when in operative position being adapted to abut directly against the sides of said central column so that upward 60 thrust of each leg is resisted by the entire end faces of the arms abutting against both the column and legs.

BENJAMIN F. VANDERSLICE.
